INVENTOR.
Joseph W. Myers
BY
Raymond A. Parker
ATTORNEY.

UNITED STATES PATENT OFFICE.

JOSEPH W. MYERS, OF JACKSON, MICHIGAN, ASSIGNOR TO HINCKLEY-MYERS COMPANY, OF JACKSON, MICHIGAN, A CORPORATION OF MICHIGAN.

CYLINDER-BORING MACHINE.

Application filed June 27, 1921. Serial No. 480,519.

To all whom it may concern:

Be it known that I, JOSEPH W. MYERS, a citizen of the United States, residing at Jackson, county of Jackson, State of Michigan, have invented a certain new and useful Improvement in Cylinder-Boring Machines, and declare the following to be a full, clear, and exact description of the same, such as will enable others skilled in the art to which it pertains to make and use the same, reference being had to the accompanying drawings, which form a part of this specification.

My invention relates to cylinder boring machines and a special object of my improvements is to provide an improved apparatus for reboring the cylinders for automobile engines.

In the accompanying drawings:

20 Figure 1 is a perspective view of an apparatus embodying my invention.

Fig. 2 is an elevation of a part of the same to an enlarged scale.

25 Fig. 3 is a detailed plan view partly in section on the line III—III Fig. 2.

Fig. 4 is a detailed elevation partly in section on the line IV—IV Fig. 2.

Fig. 5 is a sectional detail of the lower end of the boring bar.

30 Fig. 6 is a detail section on the line VI—VI Fig. 1.

a is the bed of the machine having transverse securing slots *a*⁴ therein. *a*² is the standard rising from the bed *a* and *a*³ is the overhanging portion of the frame.

35 *b* is the screw threaded boring bar. *b*² is a cylindrical rod fitting and adapted to reciprocate vertically in an aperture through and concentric with the boring bar. This 40 is provided with a handle *b*³ at its upper end, fits closely in sleeves in the boring bar as indicated in Fig 5 and its lower end is adapted to extend and fit into a sleeve in the bed *a*.

45 *c* *c*², Figs. 2 and 3, are the two constituent halves of a centering tool adapted to be secured toward the lower end of the bar *b*² and provided with handles *c*³.

x is a cylinder casting.

50 *f*² is a ring somewhat larger than the bore of the cylinder to be operated upon and having an annular projection *f* extending upward and axial therewith. The ring *f*² is sleeved over the boring bar *b* and may recip-

rocate thereon. Said ring is provided with 55 a split conical sleeve *y* (Fig. 6) with an adjusting nut *y*² by which it can be brought into close engagement with the boring bar.

e is a yoke having two opposite laterally extending arms and a central annular portion which is sleeved over the annular projection *f* of the ring *f*² and is pivotally secured to said ring by the transverse horizontal pivot pins *fe*. The yoke *e* is provided at its center and on each side of the projection *f* with a downwardly projecting portion *e*³ having a curved lower face or rocker engaging against the upper surface of the ring *f*² where it forms a shoulder adjacent to the projection *f*. *e*² *e*² are slots formed in 70 the sides and at the ends of the arms *e*.

d *d* are rods provided with heads at their lower ends adapted to engage in the slots *a*⁴ and having their upper ends screw-threaded as shown at *d*² *d*². The rods *d* are adapted 75 to engage in the slots *e*² with a relative lateral movement. *d*³ *d*⁴ are nuts having interior screw threads engaging the screw threads *d*² on the rods *d*. These nuts are provided with hand wheels or means by 80 which they may be manipulated to adjust them vertically.

The operation of the above described apparatus is as follows:

The casting *x* is placed upon the bed *a* 85 with the cylinders *x*² extending vertically.

The tool *c* *c*² is then placed upon the rod *b*² as shown in Fig. 2 and the rod is lowered into the bore of one of the cylinders and into the sleeve of the bed *a*. The casting *x* 90 being adjusted in its position on the bed until the conical tool *c* *c*² accurately engages the walls of the bore of the cylinder. This will bring the cylinder to be bored accurately axially in line with the boring bar. The 95 tool *c* and *c*² is then raised, by means of the rod *b*² and handles *b*³, out of engagement in the bore of the cylinder and removed from the bar *b*² by separating the halves *c* *c*².

100 The ring *f*² is then adjusted in position upon the upper surface of the cylinder block *x*. The rods *d* are engaged in the slots *e*² *e*² and the nuts *d*³ *d*⁴ are screwed up until the yoke *e* presses the ring *f*² firmly against 105 the surface of the block *x* thus rigidly clamping the latter upon the bed *a* in position to be bored. The boring bar *b* and the

cutting tool on the end thereof is then operated in the usual way to bore out the cylinder.

g g are brackets secured to the lower surface of the overhanging portion a³ of the frame a, a², a³.

When one cylinder has been bored the yoke e is released by screwing upward on the nuts d³ d⁴ and throwing the rods d out of engagement with the yoke e. Said yoke with the attached ring f² is then raised upward and rotated to engage in the brackets g g where it is held out of the way for subsequent use.

15 The above construction facilitates the clamping operation in that it is not necessary to screw the nuts d³ and d⁴ down absolutely evenly as the yoke may rock about the pivot pin fe and upon the engaging surfaces between said yoke and the collar f².

The ring f² being clamped to the cylinder block and fitted closely to the boring bar as above described supports said bar and prevents any vibration thereof.

25 The yoke and ring f² are preferably constructed as surrounding the boring bar but the functional feature, of course, is the position of the yoke relative to the bar, that it is in juxtaposition and has a relative 30 longitudinal movement relative thereto so as to serve the purpose of the construction.

The range of equivalents in the claims includes such equivalent constructions.

Claims:

35 1. The combination of a boring machine having a bed and a boring bar, a clamping yoke surrounding said bar and having laterally extending arms, bolts engaging said bed and engaging said arms toward the ends 40 thereof, and adjustable parts on said bolts causing said yoke to clamp the casting in position on the bed, and an annular part surrounding said bar located between said casting and said yoke, the yoke being pivoted to said annular part.

2. The combination of a boring machine having a bed and a boring bar, a clamping yoke surrounding said bar and having laterally extending arms, bolts engaging said bed and engaging said arms toward the ends thereof, and adjustable parts on said bolts causing said yoke to clamp the casting in position on the bed, said boring bar having a central aperture therethrough, a longitudinally movable rod passing through said aperture, a centering tool adapted to be secured to the lower end of said rod and to be

laterally removed therefrom for centering the casting, said rod being adapted to be manipulated from the upper end thereof to operate said tool.

3. The combination of a boring machine having a bed and a boring bar, a clamping yoke surrounding said bar and having laterally extending arms, bolts engaging said bed and engaging said arms toward the ends thereof, and adjustable parts on said bolts causing said yoke to clamp the casting in position on the bed, said boring bar having a central aperture therethrough, a longitudinally movable rod passing through said aperture, a centering tool adapted to be secured to the lower end of said rod for centering the casting, said rod being adapted to be manipulated from the upper end thereof to operate said tool, said rod engaging the bed of the machine at its lower end.

4. The combination of a boring tool having a boring bar, a yoke surrounding said bar and adapted to be oscillated about the same in a plane at right angles to the axis thereof, means engaging said yoke to clamp the cylinder casting in place, and a bracket g adapted to receive and hold said yoke in inoperative position when said yoke is moved along said bar and is rotated about the same, substantially as and for the purpose described.

5. The combination of a boring machine having a bed and a boring bar, a clamping yoke surrounding said bar and having laterally extending arms, bolts engaging said bed and engaging said arms toward the ends thereof, and adjustable parts on said bolts causing said yoke to clamp the casting in position on the bed, and adjustable means on said yoke for engaging and steadyng said bar.

6. The combination with a boring machine having a bed and a boring bar of a clamping yoke surrounding said bar and having laterally extending arms, lateral slots in the ends of said arms, bolts engaging said bed and engaging in said slots by a lateral movement and adjustable parts on said bolts causing said yoke to clamp the casting in position on the bed, and an annular part surrounding said bar located between said casting and said yoke, the yoke being pivoted to said annular part.

In testimony whereof, I, JOSEPH W. MYERS sign this specification.

JOSEPH W. MYERS.
